UNITED STATES PATENT OFFICE.

JOSEPH VAUGHAN, OF ASHLAND, VIRGINIA.

CORE FOR CONCRETE STRUCTURES.

No. 891,883.

Specification of Letters Patent. Patented June 30, 1908.

Application filed February 6, 1908. Serial No. 414,557.

To all whom it may concern:

Be it known that I, JOSEPH VAUGHAN, a citizen of the United States, residing at Ashland, in the county of Hanover and State of Virginia, have invented certain new and useful Improvements in Cores for Concrete Structures, of which the following is a specification.

My invention relates to cores for forming hollow spaces in concrete walls, and its object is to provide a device of the class described which shall be sufficiently rigid for the purpose for which it is used; which may be easily withdrawn from the wall; and which shall be economical in construction.

In the accompanying drawings, which form a part of this specification, and in which like numerals refer to like parts in the several views:—Figure 1 is a view of the core in plan, and shows the core locked and ready for use in forming a hollow space in a concrete wall; Fig. 2 is a vertical section taken on line *a*—*b* in Fig. 1; Fig. 3 shows, in plan, the core collapsed, and ready to be withdrawn from the wall, or to be raised to a higher position; and Fig. 4 is a vertical section taken on line *c*—*d* in Fig. 2.

In Fig. 1 side plates 1, 2 and 4, 5 are hinged together, respectively, at the points 3 and 6. End plates 7, 8 and 10, 11 are hinged together, respectively, at the points 9 and 12. The hinged side plates and the hinged end plates are themselves hinged together at the points 13.

On the plates 1, 5, 7 and 10 are pivoted the locking bars 14, 14 and 15, 15. These bars are arranged to swing across the adjacent hinges 3, 6, 9 and 12; and to drop into the catches 16; and they are so fitted in relation to the parts to which they are attached that the latter are held rigidly in position when they, the bars, are inserted in the catches. For instance, when the bar 14 which is pivoted to the side plate 1 is dropped into its catch 16, the two plates 1 and 2 are held rigidly in line with one another; the hinge 3 being prevented from opening. In the drawings only one locking bar has been shown on each side of the core. More than one may be so used if found advisable owing to the depth of the core.

The locking bars are provided with projecting parts 17, 17 and 18, 18; the said projecting parts affording means by which the bars may be operated through the medium of a hooked rod. For instance, when it is

desired to unlock the bars 14, the rod is caused to catch in the projecting part 17, and is then pulled upwards; the bar being thus lifted from the catch 16.

When the concrete wall has set sufficiently for the core to be withdrawn, the locking bars 14 and 15 are lifted from the catches 16, permitting the hinges 3, 6, 9 and 12 to operate inwardly, thus collapsing the core (see Fig. 3). The core now covers a smaller area, or in other words its overall dimensions are less, than when it is locked in position as in Fig. 1; and consequently it can be readily removed from the wall, or raised to a higher position.

In Fig. 2 is shown a projecting lug or pin 19. Like pins are placed in similarly relative positions to each of the locking bars. When the bars are lifted from the catches, and the core is collapsed, the bars fall until they rest on these pins, and are by them prevented from falling so far as to make it difficult to reset them when the core is to be again locked in position.

Having now described my invention, what I claim, and desire to protect by Letters Patent of the United States, is:—

1. A collapsible core having hinged side plates and hinged end plates, means for locking the hinges of the said side and end plates, and hinges connecting the side and end plates.

2. In a collapsible core, the combination of side plates having inwardly operating hinges about their centers, end plates having inwardly operating hinges about their centers, means for locking the said hinges, and hinges connecting the side plates and end plates.

3. In a collapsible core, the combination of side and end plates, said side plates being fixedly connected with said end plates at their adjacent ends, flexing means for bringing towards one another the extremities of the said side and end plates, and means for counteracting the flexing means so that the extremities of the said side and end plates may be held at their greatest distance apart.

4. In a collapsible core, the combination of side plates and end plates, said side plates being flexibly connected with said end plates at their adjacent ends, inwardly operating flexing means for bringing toward one another the extremities of the said side plates and end plates, and means for counteracting the flexing means so that the extremities of

the said side and end plates may be held at their greatest distance apart.

5. In a collapsible core, the combination of side plates and end plates, said side and end plates being connected together at their adjacent ends, inwardly operating flexing means for bringing toward one another the extremities of the said side and end plates, and means for counteracting the flexing 10 means so that the extremities of the said side and end plates may be held at their greatest distance apart.

6. In a collapsible core, the combination

of the side plates 1, 2, 4 and 5, the said side plates having hinges 3 and 6; end plates 7, 8, 15 10 and 11, the said end plates having hinges 9 and 12; the locking bars 14 and 15; the catches 16; and means for connecting the side and end plates.

In testimony whereof I affix my signature, 20 in presence of two witnesses.

JOSEPH VAUGHN
